CONVERTIBLE CHAIR

John E. Beardmore, Chicago, Ill., assignor to Karoll's Inc., Chicago, Ill., a corporation of Illinois

Filed Feb. 16, 1968, Ser. No. 10,601

Term of patent 14 years

Int. Cl. D6—01

U.S. Cl. D15—1

FIG. 2 is a front elevational view thereof;

FIG. 3 is a rear elevational view thereof;

FIG. 4 is a side elevational view thereof;

FIG. 5 is a top plan view thereof;

FIG. 6 is a bottom plan view with a portion thereof broken away; and

FIG. 7 is a cross-sectional view taken along vantage line 7—7 of FIG. 2 and looking in the direction of the arrows thereon.

I claim:

The ornamental design for a convertible chair, as shown.
